UNITED STATES PATENT OFFICE.

EARL S. RAU, OF ELKINS PARK, PENNSYLVANIA.

ELECTRICALLY-CONTROLLED INDICATOR.

1,260,450.

Specification of Letters Patent. Patented Mar. 26, 1918.

Application filed November 29, 1916. Serial No. 134,126.

To all whom it may concern:

Be it known that I, EARL S. RAU, a citizen of the United States, residing at Elkins Park, in the county of Montgomery and 5 State of Pennsylvania, have invented a certain new and useful Improved Electrically-Controlled Indicator, of which the following is a specification.

The invention broadly stated relates to 10 electrically controlled indicators and has more particular relation to an indicator for use upon moving passenger carriers, such as electric cars. The principal object of the present invention is to provide a simple, efficient and relatively inexpensive street or 15 station indicator for electric cars for automatically displaying in sequential relation the streets or stations as approached, wherein provision is made for the electrical 20 cutting out of the indicator operating mechanism immediately the indication is displayed. Other and further objects of the present invention reside in the provision of novel and automatic devices coöperating in 25 a practical manner for advancing a band or ribbon having delineated thereon the names of streets or stations. With these and other objects in view the invention consists of the improvements hereinafter described and 30 finally claimed.

The nature, characteristic features and scope of the invention will be more fully understood from the following description taken in connection with the accompanying 35 drawing forming part hereof and in which:

Figure 1 is a diagrammatic view illustrating the circuit connections of the invention for operating an indicator for electric cars.

Fig. 2 is a similar view illustrating a 40 trolley wire connection at a street crossing or station, and

Fig. 3 is a detail view hereinafter referred to.

For the purpose of illustrating my invention, I have shown in the accompanying drawings one form thereof which is at present preferred by me since the same has been found in practice to give satisfactory and reliable results, although it is to be under-

50 stood that the various instrumentalities of which my invention consists can be variously arranged and organized and that my invention is not limited to the precise arrangement and organization of the instrumentalities as herein shown and described.

In the drawings 10 designates a trolley

wire supported as upon stringers 11, between poles 12 and 13 at a street crossing or station as may be along an electric car line. Paralleling the trolley wire 10 in advance of a street or station is a short section or auxiliary wire 14 which may be supported between adjacent stringers 11 as shown in Fig. 2 or in any other desired manner. Such auxiliary wire is alive at all 60 times. The trolley pole 15 of a car (not shown) is provided with an auxiliary trolley 16 adapted for tracking upon the auxiliary wire 14 as a car approaches a street or station. Electrically connecting with auxiliary 65 trolley 16 is conductor 17 which sub-divides, one wire 18 leading to a solenoid 19 or electro-magnet and the other wire 20 leading to a solenoid 21 or electro-magnet. From solenoids 19 and 21 wires 22 and 23 lead to a 70 conductor 24 which is grounded, for instance, through the motor of a car. Within the solenoid circuit thus formed is located a switch 25, the purpose of which will presently appear. Located adjacent the solenoids 19 and 21 are contacts 26 and 27 of 75 which contact 26 is electrically connected by wire 28 with conductor 18 and contact 27 is electrically connected by wire 29 with solenoid 30 which in turn is connected by 80 wire 31 with the return conductor 24 at a point between switch 25 and connection of wire 22 with the return conductor 24. Below solenoids 19 and 21 is located a pivoted 85 detent 32 for releasing at predetermined 90 periods an escapement 32' of roller 32" of a reel for the display of a street or station designation. Such reel may be of any desired construction. The detent 32 is provided at its free end with a contact piece 34 95 disposed in alinement with solenoid 21 and with the energizing of said solenoid, said free end of the detent is drawn up free of the escapement. The detent is further provided with a movable contact piece 35 for 100 bridging the oppositely disposed contacts 26 and 27, when the solenoid 19 is energized, see Fig. 3. In this respect, it may be stated that the contact piece 35 is fixed upon a pin 36 of insulating material but is relatively movable with respect to said detent. Thus as solenoid 21 draws up the detent, solenoid 19 draws up the contact piece 35 105 bridging said contacts 26 and 27. With the bridging of contacts 26 and 27 current passes 110 to and energizes solenoid 30 or electro-magnet, which solenoid operates switch 25 to

break the circuit within which is located solenoid 21 thereby deenergizing the latter and permitting detent 32 to assume its normal position, the reel in the meantime having advanced a predetermined distance for proper display of street or station designation. The detent 32 as shown is spring controlled for rapid and positive return to normal position, as is the switch 25. The lower roller 36 may also be provided with a spring to insure positive reel movement.

In operation, as a car nears a street crossing or station, the auxiliary trolley rides upon the short section or auxiliary trolley wire and energizes the solenoids 19 and 21, whereby the detent is raised free of the upper reel roller to permit the latter to operate. At the same time, the movable contact of the detent is raised by solenoid 19 to bridge contacts 26 and 27, see Fig. 3, with the result that current passes to and energizes solenoid 30 which opens switch 25 thereby deenergizing solenoid 21 to permit detent to assume its normal position. It is to be observed that these solenoids are properly proportioned for co-operatively accomplishing the above operations.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modifications in various particulars without departing from the spirit or scope 40 of the invention or sacrificing any of its advantages.

What I claim is:

1. Apparatus of the character stated comprising an indicator provided with an escapement, an electrical circuit, an electro-magnet in said circuit, a detent for releasing the escapement upon energizing of said electro-magnet, a bridge piece movably carried by and insulated from said detent, spaced 45 contacts and an electro-magnet adjacent thereto also disposed in said circuit, said bridge-piece upon energizing of said second electro-magnet being drawn up into bridging relation with said contacts and means 50 located in said circuit operative for deenergizing the detent operating electro-magnet when said contacts are bridged.

2. Apparatus of the character stated comprising an indicator provided with an escapement, an electrical circuit, an electro-magnet in said circuit, a pivotal detent for releasing the escapement upon energizing of said electro-magnet, a non-metallic pin carried by the detent and movable with respect thereto, a bridge piece fixed upon said pin, 60 spaced contacts and an electro-magnet adjacent thereto also disposed in said circuit, said bridge piece upon energizing of said second electro-magnet being drawn up into bridging relation with said contacts and a 70 switch and electro-magnet adjacent thereto located in said circuit which electro-magnet is operative for opening said switch to deenergize the detent operating electro-magnet with the bridging of said contacts. 75

3. Apparatus of the character stated comprising an indicator provided with an escapement, an electrical circuit, an electro-magnet in said circuit, a detent for releasing the escapement upon energizing of said electro-magnet, contact-means and an electro-magnet adjacent thereto also disposed in said circuit, means carried by, insulated from and movable with respect to said detent for contacting with said contact-means 85 upon energizing of said second electro-magnet and means located in said circuit for deenergizing the detent operating electro-magnet upon effecting of said contact.

4. Apparatus of the character stated comprising an indicator provided with an escapement, an electrical circuit, an electro-magnet in said circuit, an apertured detent for releasing the escapement upon energizing of said electro-magnet, a member having 90 a stop movable through the aperture in said detent but insulated therefrom, a bridge piece carried by said member, contacts and an electro-magnet adjacent thereto also disposed in said circuit, said bridge piece upon 100 energizing of said second electro-magnet being drawn into bridging relation with said contacts and a switch and an electro-magnet adjacent thereto located in said circuit which electro-magnet is operative for opening said 105 switch to deenergize the detent operating electro-magnet with the bridging of said contacts.

In testimony whereof, I have hereunto signed my name.

EARL S. RAU.
